ELECTRIC CONTACT MAKING AND BREAKING DEVICE

Application filed December 12, 1928, Serial No. 325,633, and in Great Britain December 20, 1927.

This invention relates to means of the kind whereby a movable body actuated by weak electric forces, can be used for making and breaking electrical connection between two conductors for bringing into action some electrical device, as for instance a thermionic valve, or a sensitive relay, for effecting some useful purpose.

To this end, it has been proposed to cause 10 a movable conductor adapted to be actuated by a weak electrical force, to make contact with a stationary conductor or conductors in the form of a stretched or free wire or wires. Also, it has been proposed to cause 15 two movable conductors actuated alternately in opposite directions by weak positive and negative signals or charges, to make contact alternately with two stationary stretched wires. In each of these cases, im- 20 perfect contact is sometimes produced between the movable conductor or conductors and the fixed wire or wires, due to the resilience of the wire or wires, which causes the movable conductor or each movable con- 25 ductor, after being momentarily brought into contact with the associated wire, to rebound suddenly therefrom. Sparking and stick- 30 ing of contacts also sometimes occur.

An object of the present invention is to 35 provide a contact making and breaking device wherein the movable conductor or each movable conductor, when moved into elec- 40 trical connection with its associated station- 45 ary conductor, will not rebound therefrom, but will, on the contrary remain in firm contact therewith until positively moved there- 50 from so that the above named disadvantages of the known arrangements shall be avoided.

For this purpose in a circuit making and 55 breaking device constructed according to the present invention, the stretched wire, or each stretched wire, of the known arrange- 60 ments, is replaced by a conductor consisting of a piece of soft non-resilient material hav- 65 ing a moist conducting surface. By this means, when the movable conductor is 70 brought into contact with the moist surface of the soft non-resilient stationary conductor, it will not rebound therefrom but will, 75 on the contrary, be held in effective contact

therewith, by reason of the moisture present causing adhesion between the two conductors until the movable conductor is positively moved away from the stationary moist conductor. In this way, a continuous and effective connection can be maintained between the two conductors for any desired time. 55

The moist soft-non-resilient stationary conductor (hereinafter called for brevity the moist conductor) can be variously constituted. Thus, it may consist of a small pad 60 of porous material mounted upon a suitable support and moistened with a conducting liquid, for instance water, in any convenient way, as by capillary action, a part of the said 65 material dipping for this purpose into liquid contained in a receptacle carrying the support and pad. Or, as is preferred, the moist conductor consists of a length of thread, string or like material kept in a taut condition and moistened with a conducting material. Two more lengths of such material may sometimes be used. The movable conductor may consist of a length of stiff wire. Two or more of such conductors may be used 70 with one or more moist conductors and be operated in various ways by a device sub- 75 ject to the action of weak electric forces.

In the accompanying illustrative draw- 80 ings, Figs. 1 to 5 inclusive show, diagram- 85 matically, various arrangements of electric contact making and breaking devices, em- bodying the invention.

In the example shown in Fig. 1, the moist conductor consists of a length 1 of thread or 85 string that is kept in a stretched condition and is supplied with conducting liquid 3 from a small cell or receptacle 4 therefor so that it will continually be kept in a moist condition. 5 is a movable conductor, consisting of a 90 length of stiff wire, adapted to coact with the moist conductor 1.

When weak electric forces are to be utilized, that act alternately in opposite direc- 95 tions, as for example weak positive and negative signals in land or submarine telegraph lines or cables, a single movable conductor 5 responsive to such signals may be arranged to move to and fro between two moist con- 100 ductors 1, 1^a as shown in Fig. 2. Or two op-

positively movable conductors 5, 5^a adapted to be actuated by the oppositely acting electrical forces may, as shown in Fig. 3, be associated with two separate moist conductors 1, 1^a of the kind described and to and from which they are respectively moved for the purpose of making and breaking electric connections between them.

When using a piece of thread or string as described, it may, as shown in Fig. 1, be connected at one end to the receptacle 4 containing the liquid 3, and at its other end to a bent over portion 6^a of a stem 6 of resilient wire fixed to the receptacle 4, the lower end of the string being in contact with the conducting liquid 3 so that the whole length of the string will be wetted by capillary action, whilst it will be held in a stretched or taut condition by the bent over portion 6^a of the piece of wire, acting as a spring. If two lengths of string be used, their upper ends may, as shown in Fig. 3 be connected to two bent over spring portions 6^a, 6^a of wire carried by a single stem 6, or it may be by separate stems. The movable conductor or conductors may be moved towards and against the stationary moist conductor or conductors by a returning force, for instance a spring or springs, and be moved away from the moist conductor or conductors by a weak electrical force or forces, against the action of the returning force, which acts to return it or them to the moist conductor or conductors when the electrical force ceases to act, or to act with insufficient force to overcome the returning force.

The electrical device subject to weak electrical forces and used for moving the movable conductor or conductors away from the moist conductor or conductors may for example, be a coil that is subject to the action of weak electrical currents or charges and is suspended in a permanent magnetic field formed between the oppositely arranged north and south poles of a permanent magnet, as in telegraphic apparatus used with a submarine cable and siphon recorder, the coil being normally held in a mid-position by torsion means and provided with a light arm for actuating the movable conductor or conductors in accordance with electrical signals received by such coil.

Contact making and breaking devices with associated controlling means and controlled means, according to the invention, can be variously constructed and arranged to suit different requirements.

Fig. 4 shows by way of example, one arrangement comprising two spring controlled movable conductors 5, 5^a connected to the respective grids of two thermionic valves 7 and 8 and arranged to co-act with two stationary moist conductors 1, 1^a connected to the grid circuits of the valves through a grid bias battery 9, the two movable conductors be-

ing arranged to be moved alternately from their respective moist conductors by an arm 7^x actuated by a suspended coil 10, such as hereinbefore referred to, designed to be traversed by weak positive and negative signals. 70 11 and 12 are high resistances connected between the grids of the two valves and the battery 9. The two thermionic valves 7 and 8 may be arranged to actuate means, for instance relays 13 and 14. The arrangement is 75 such that when the conductor 5 is moved away from the moist conductor 1 by the arm 7^x under the action of say a positive signal or impulse traversing the coil 10, the thermionic valve 7 will act to cause its associated relay 13 to reproduce or record a corresponding positive signal and when the movable conductor 5^a is moved away from the moist conductor 1^a by a negative signal or impulse, the corresponding thermionic valve 8 will act to cause its associated relay 12 to reproduce or record a corresponding negative signal. Each movable conductor 5 and 5^a may, as more clearly shown in Fig. 5 be rigidly connected to but insulated from a straight 80 length 15 of wire arranged at right angles to it and fixed at its ends 15^a, 15^b, each such length of wire including a torsion spring 16 adapted to move the conductor 5 or 5^a towards and against its corresponding moist conductor 1 or 1^a when the movable arm 7^x permits it to do so. 90

We claim:

1. An electric contact making and breaking device comprising a conductor of non-resilient material having a moist conducting surface, a metal conductor, and means for moving the said conductors into and out of contact. 100

2. An electric contact making and breaking device comprising a conductor of non-resilient material, means for keeping the said conductor moistened, means for holding the said conductor taut, a metal conductor and means for moving the said conductors into and out of contact. 105

3. An electric contact making and breaking device comprising a vessel containing a conducting liquid, a thread supported above and extending into said liquid, a metal conductor and means for moving said metal conductor into and out of contact with said thread. 115

4. An electric contact making and breaking device comprising a vessel containing a conducting liquid, two threads separately supported and extending into said liquid, two metal conductors and means for moving one metal conductor into contact with one thread, and the other metal conductor out of contact with the other thread, or vice versa. 120

5. In a thermionic relay, comprising in combination, an electric contact making and breaking device containing a conducting liquid a thread extending into said liquid, a metal conductor, a space discharge device 130

- having an input circuit and an output circuit, electric circuit leads connecting said thread and said metal conductor to the input circuit of said space discharge device, means for moving said metal conductor into and out of contact with said thread, and means in the output circuit of said space discharge device for recording said movement.
6. In a thermionic tube relay, comprising in combination, an electric contact making and breaking device comprising a vessel containing a conducting liquid, two threads extending into said liquid, means for keeping both of said threads taut, two space discharge devices each having an input circuit containing a resistance and an output circuit, electric circuit leads connecting said conducting liquid to one terminal of each resistance, two metal conductors, electric circuit leads connecting said conductors to the other terminals of the respective resistances, means for moving the metal conductors into or out of contact with the respective threads, and means in the output circuit of said space discharge devices for recording the movement of said metal conductors.
7. In combination, moist and dry conductors, means for moving said conductors relatively into and out of contact, a recording device and means for rendering said recording device operative upon opening of said contact.
8. In combination, moist and dry conductors, impulse responsive means for moving said conductors relatively into and out of contact, a recording device and space discharge means for actuating said recording device.
9. In combination, impulse responsive means, spaced moist conductors, a movably disposed dry conductor associated with each moistened conductor, means operated by said impulse responsive means for alternately actuating said movable conductors to contact their associated moist conductor, a thermionic device associated with each moist and dry conductor, normal biasing and actuating electromotive forces, grid leaks in multiple with said electromotive forces, a plate circuit and means disposed in said circuit for recording impulses of opposite polarities traversing said impulse responsive means.
10. In combination, signal responsive means, means carried thereby for opening or closing a contact comprising a moist and dry portion, space discharge means, impulse recording means operatively associated with said space discharge means, means responsive to the opening of said contact for actuating said discharge device to render operative said recording means.
11. In combination, signal responsive means, means carried thereby for opening or closing a contact, the latter comprising a wet conducting portion and dry conducting
- portion, space discharge means rendered effective upon opening of said contact, and recording means responsive to the operation of said space discharge means.
12. In combination, signal responsive means, contact opening and closing means comprising moistened and dry conductors, space discharge means, impulse recording means operatively associated with said space discharge means, said signal responsive means comprising means to actuate said contact closing and opening means for contacting said wet with said dry conductors alternately whereby an impulse through said signal responsive means is repeated by said recording means.
13. An electric contact making and breaking device comprising a conductor having a moist conductor surface, a metal conductor, and means for moving the said conductors into and out of contact.
14. An electric contact making and breaking device comprising a conductor, means for keeping the said conductor moistened, means for holding the said conductor taut, a metal conductor and means for moving the said conductors into and out of contact.
- In witness whereof, we hereunto subscribe our names.
